(57) **CLAIM**

The ornamental design for a candlestick, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective photographic view of a candlestick showing my new design;

FIG. 2 is a rear perspective photographic view thereof;

FIG. 3 is a front photographic view thereof;

FIG. 4 is a rear photographic view thereof;

FIG. 5 is a left side photographic view thereof; and,

FIG. 6 is a right side photographic view thereof.

The broken line adjacent the photographic area represents a boundary of the design and forms no part thereof. The broken lines form no part of the claimed design.
